C. H. RIPPL.
 MAGNETICALLY OPERATED DEVICE.
 APPLICATION FILED APR. 18, 1913.
1,144,063. Patented June 22, 1915.

UNITED STATES PATENT OFFICE.

CHARLES H. RIPPL, OF CLEVELAND, OHIO, ASSIGNOR TO THE ELECTRIC CONTROLLER AND MANUFACTURING COMPANY, OF CLEVELAND, OHIO, A CORPORATION OF OHIO.

MAGNETICALLY-OPERATED DEVICE.

1,144,063.

Specification of Letters Patent. Patented June 22, 1915.

Application filed April 18, 1913. Serial No. 761,972.

To all whom it may concern:

Be it known that I, CHARLES H. RIPPL, a citizen of the United States, residing at Cleveland, in the county of Cuyahoga and State of Ohio, have invented new and useful Improvements in Magnetically-Operated Devices, of which the following is a specification.

My invention relates to magnetically-operated devices, particularly those in which the armature of the magnet oscillates about a pivot.

The objects of my invention are to secure intimate contact of the armature with the poles of an electro-magnet, to prevent the humming or chattering of the armature, and to increase the holding power of the magnet.

Other objects and advantages will appear in the following description.

Referring to the accompanying drawings, Figure 1 is a front elevation of my improved magnet in connection with an electric switch. Fig. 2 is a side elevation, partly in section, and Fig. 3 is a cross section of the armature taken through the supporting pin and bearing bolts. Fig. 4 is a section on the line IV—IV, Fig. 1, and Fig. 5 is a section on the line V—V, Fig. 1.

On the support 1, which is preferably of insulating material, is mounted a U-shaped core 2 made up of laminations vertically arranged. These laminations are held together in some suitable way, but I preferably weld them together, or weld them to strips 3 at the back of the magnet. The magnet may be fastened to the support 1 by means of the bolts 4 which pass through the strips 3. The energizing winding 5 is shown surrounding one leg of the core 2. The armature 6 is also composed of laminations, and I prefer to hold these together by welding them to a U-shaped holder 7, the weld being made on the surface 8 or at the edges 8^a. Plates 9 and 10 are, respectively, also welded to the laminations of the core 2 and the armature 6, and I prefer to place these in such position that they will form the engaging surfaces of the magnet poles and the armature. This arrangement protects the laminations from being injured by the impact of the armature against the poles. Eddy currents are set up in the plates 9 and 10 which produce a flux out of phase with the flux set up in the laminations by

the energizing winding, thereby causing a magnetic pull to exist between the armature and magnet during the reversal of the current in the winding.

For supporting the armature, the holder 7 is provided with a lug 7^a through which the pin 17 passes. The armature 6 is supported by a lever 11, which is mounted on the shaft 12. This shaft is supported by suitable bearings 13, bolted to the supporting frame 1. The lever 11 has an arm 14 which engages a stop 15 to limit the opening movement of the armature.

In order that the armature may have a free movement, so that the surfaces of the opposing plates 9 and 10 will fully engage each other, the armature is attached to the holder by a pin 17 which extends through the two lugs 11^a on the front of the lever, and through the lug 7^a on the front of the holder 7. This pin is fastened to one lug 11^a by a small pin 18. The pin 17 is within the lug 7^a rounded or barrel-shaped so that the armature can oscillate slightly laterally, or in a horizontal direction. The lever 11 has its sides overlapping the sides of the holder 7. Bearing bolts 19 pass through the sides of the lever 11 and the holder 7 and bear against the outer surfaces of the armature 6, there being a slight clearance left to allow the free movement of the armature in its lateral oscillation on the pin 17.

I have found that there is less humming and chattering if the armature in closing is arranged to engage its lower plate 10 with the lower plate 9 before the upper plates 9 and 10 engage. In order to bring this about I have provided for the pin 17 a vertical oblong hole in the lug 7^a, so that the holder may oscillate to a limited extent vertically about the bearing bolts 19. The said oblong hole is indicated by the dotted lines 20. In order that the armature may oscillate freely laterally, the U-shaped holder 7 is provided with the horizontal slots 21 for the bolts 19, which slots allow the armature to slide upon the bearing bolts 19, and permit the rear face of the armature to adjust itself in the same vertical plane as the poles of the core 2.

When the armature is in the open position, the weight of the armature causes its rotation in a counter clockwise direction about the bearing bolts 19 to the extent determined by the oblong hole 20. When the

winding 5 is energized, the armature is attracted, and in closing against the surfaces of the magnet 2, the lower plate 10 first engages the lower plate 9, and as the armature 5 is pulled home the upper plates 9 and 10 then engage. The magnetic pull between the magnet and armature causes the armature to find its seat with the plates 9 and 10 intimately engaging one another, a slight 10 rotation of the armature taking place about the bearing bolts 19, and a slight movement also taking place between the pin 17 and the oblong hole 20 in the lug 7^a. Since the lower plates 9 and 10 first engage, there will be 15 slightly more wear on these plates than on the upper plates. Allowance is made for a sufficient rotation about the axis through the bearing bolts 19 to always cause the lower plates to first engage until they are entirely 20 worn away. These plates may be made of hard steel, so that the amount of wear will be very slight. I have found by actual count that a magnet constructed in this way will operate as many as twelve million times 25 without causing serious wear on the plates and without causing injury to the engaging surfaces of the magnet or armature. As a matter of fact, the condition of the surfaces improves as the number of operations increases. 30

I have shown my improved magnet arranged to operate an electric switch. This switch has a movable member 22 mounted on the portion 12^a of the shaft 12. The 35 member 22 carries a contact 23, which is arranged to engage a relatively stationary contact 24. The contact 24 is carried by a holder 25 pivoted at 26 to a holder 27, the holder being bolted to the support 1 by bolts 40 28. The contact 24 is held in its outermost position by the compression spring 29, the outward movement being limited by a stop 30. The contact 23 is insulated from the member 22 by an insulating member 31.

45 In order that the contact 23 may have a slight travel in the closing direction after the movement of the armature 6 has been arrested upon engagement with the core 2, I provide a coupling 32 carried by the portion 12^a 50 of the shaft 12. This coupling has a slot 33 which is engaged by the projection 34 carried by the lower portion of the magnet holder. This holder is free to revolve on the shaft 12. When the armature 6 55 to the magnet, the projection 34 engages the coupling 32 at the surface 35, causing the shaft to turn and thereby causing the switch contacts to engage. When the armature 6 engages the core 2, the shaft and the contact 60 23 can continue their movement slightly, until their momentum is overcome, after which the spring 29 causes the contacts to return to the position shown in the drawing.

65 It will be readily understood by those skilled in the art that my invention may as-

sume other forms than those shown in the drawings, without departing from the spirit of my invention as set forth in the following claims.

I claim:

1. In a magnetically-operated device, a magnet with poles, an armature normally separated from the poles but adapted to engage the same, a pivot for the armature, an energizing winding, and means for causing the armature to first engage the magnet pole nearest the pivot. 70

2. In a magnetically-operated device, a core, an energizing winding, an armature therefor, a perforated lug on the pack of the armature, a barrel-shaped bearing-pin in the perforation in the lug to make the armature free to move in two or more directions, and means for causing the same portion of the armature whenever it is operated to first 85 engage the core. 86

3. In a magnetically-operated device, a magnet pole, an energizing winding therefor, an armature having a face for engaging said magnet pole, and means for supporting 90 the armature to permit it, when it engages the said pole, to have a rolling motion about an apparent longitudinal axis eccentric to the supporting means of the said armature face. 95

4. In a magnetically-operated device, magnet poles, an energizing winding, an armature normally separated from the poles, and means for causing the armature whenever it is operated to first engage the same 100 pole of the magnet. 100

5. In a magnetically-operated device, a core, an energizing winding, an armature, an axis around which the armature oscillates in its movement toward the magnet, 105 and a second axis substantially parallel to the first axis, around which the armature oscillates to cause the same to engage first one edge of the pole and then to engage the surface of the pole. 110

6. In a magnetically-operated device, a magnet portion, an armature portion, a magnetizing winding for causing the armature to engage the magnet, two supports for the armature, and means for permitting the armature to move about a transverse axis passing through one of the supports and about an apparent longitudinal axis eccentric to both supports. 115

7. In a magnetically-operated device, a magnet and an armature, one or more plates on the engaging surfaces of the magnet and of the armature, and means for causing certain plates to first engage whenever the armature is operated. 120

8. In a magnetically-operated device, a laminated magnetic structure, having stationary and movable portions, magnetic plates on the engaging surfaces thereof, an energizing winding, and means for causing 125 130

certain portions of the engaging surfaces first to engage whenever the winding is energized.

9. In an electro-magnetic device, a core, 5 an energizing winding therefor, an armature, a holder therefor, a carrier for the holder, supports in the carrier for permitting the holder to oscillate independently of the carrier in the direction of its opening 10 and closing movements, and a support for the holder for permitting the holder to oscillate transversely of the said movements.

10. In an electro-magnetic device, a core, an energizing winding therefor, an armature, 15 a holder therefor, a carrier for the holder, supports for permitting the holder to oscillate in the direction of its opening and closing movements, and for permitting the holder to oscillate transversely of the 20 said movements, the bearings for the supports being elongated to permit the holder to have said transverse oscillation.

11. In an electro-magnetic device, an electro-magnet, an armature, a holder there- 25 for, a carrier for the holder having move- ment toward and from the magnet, support- ing means for the holder borne by the car- rier and arranged substantially parallel to the face of the armature nearest the magnet,

and a second supporting means for the 30 holder borne by the carrier, and substan- tially parallel with the said first supporting means, there being a slotted connection for the second supporting means between the carrier and the holder.

12. In an electro-magnetic device, an electro-magnet, an armature, a holder there- 40 for, a carrier for the holder having move- ment toward and from the magnet, support- ing means for the holder borne by the car- rier and arranged substantially parallel to the face of the armature nearest the magnet, 45 and a second supporting means for the holder borne by the carrier, and substantially parallel with the said first supporting means, there being a slotted connection for the sec- ond supporting means between the carrier and the holder, and the second supporting means being rounded to permit the holder to oscillate at a right angle to the said first 50 supporting means.

Signed at Cleveland, Ohio, this 16th day of April, A. D. 1913.

CHARLES H. RIPPL.
